Henry Schlesinger INVENTOR

Frank P. Wentworth
his ATTORNEY.

UNITED STATES PATENT OFFICE.

HENRY SCHLESINGER, OF NEW YORK, N. Y., ASSIGNOR OF THREE-FOURTHS TO
WILLIAM J. JAEGER, OF NEW YORK, N. Y.

SAFETY-RAZOR.

1,358,115.

Specification of Letters Patent. Patented Nov. 9, 1920.

Application filed February 2, 1920. Serial No. 355,757.

To all whom it may concern:

Be it known that I, HENRY SCHLESINGER, a citizen of the United States, residing at the borough of Manhattan, city, county, and 5 State of New York, have invented certain new and useful Improvements in Safety-Razors, of which the following is a specification, reference being had therein to the accompanying drawings, which form a part 10 thereof.

My invention relates to safety razors, and more particularly to a razor of this type which is so constructed as to be capable of being made of sheet metal throughout, excepting as to the removable blade.

While a safety razor made in accordance with my invention may be made at a remarkably low cost because of its sheet metal construction, the very simplicity in its structure necessitates care in the formation of the coating parts so as to insure accuracy in the positioning of the blade with relation to the guard and avoid the presence of sharp edges which may contact with the 20 skin of the user, the edge thereof adjacent the sharpened edge of the blade being so bent upon itself as to present a short curve of sufficient thickness to act as an effective guard.

The entire guard plate is made of one sheet of metal so formed as to provide the guard above referred to, and also to provide guides for accurately positioning the edge of the blade with relation to said guard, 30 which guides also serve, in conjunction with suitable edge guides and keepers co-operating with the blade and also with a retaining plate, to develop such tensioning stresses in said retaining plate as will hold 40 the blade upon the guard plate.

The entire structure comprises but four parts, a guard plate having a handle soldered or otherwise firmly and permanently secured thereto, a razor blade and a 45 retaining or slide plate removably mounted upon said guard plate, there being no screws, bolts, rivets or other fittings necessary in the assembling of the device.

The invention consists primarily in a 50 safety razor comprising a sheet metal guard plate having one longitudinal edge thereof turned upon itself to form a guard for the edge of the razor blade, and having the opposite side edges thereof turned in the opposite direction to form guide keepers ex-

tending at right angles to said guard at opposite edges of said guard plate, said guard plate having rectilinearly arranged, upwardly extending projections between said guide keepers, and a retaining plate slidably mounted in said guide keepers and adapted to engage said projections, whereby said retaining plate adjacent the cutting edge of the blade, will be forced into engagement therewith to bind said blade upon 60 said plate; and in such other novel features of construction and combination of parts as are hereinafter set forth and described, and more particularly pointed out in the claims hereto appended.

70 Referring to the drawings,

Figure 1 is a perspective view of a safety razor embodying my invention with the retaining plate removed from the guard plate, but in position to be applied thereto;

75 Fig. 2 is a bottom plan view of the assembled structure; and

Fig. 3 is a side view thereof upon a larger scale with the guard plate, razor blade, retaining plate, and the upper portion of the 80 handle, shown in section.

Like letters refer to like parts throughout the several views.

In the embodiment of my invention shown in the drawings, *a* indicates a guard plate, 85 the forward edge of which has its sides mitered to form a flap which is bent downwardly and rearwardly upon the body of said plate to reinforce this edge of said plate *a* and at the same time form a short curved 90 surface which will serve as a guard *a'* adjacent the cutting edge of the blade *b*.

In forming the inturned flap *a'* I make it slightly shorter in width than the said plate *a* so as to leave short gage tongues *a*² which 95 may be flared upwardly slightly so as to prevent displacement of the blade in relation to the said guard portion *a'* when mounting the retaining plate in relation to said blade.

100 The side edges of said plate *a* are turned upwardly and inwardly to form the guide keepers *c* at opposite sides of the plate *a*, extending at right angles to the guard *a'* of said plate. These guide keepers afford sufficient clearance to receive the blade *b* and also to receive the retaining plate *d* which is adapted to be slidably mounted upon said plate *a* between the blade *b* and the keepers *c* in a manner to force said blade *b* firmly 110

against the plate a and hold it against possible displacement while the razor is in use. In order to develop the desired tensioning stresses upon said retaining plate d , I provide the plate a with two rectilinearly arranged projections $e-e'$ adapted to engage the under face of said plate d while it is being forced between the blade and the said keepers c , and at the same time serve as a back gage for accurately positioning the blade in relation to the guard a' .

To facilitate the insertion and removal of the plate d , I form a downwardly curved hand-hold thereon at d' and fold the edge thereof upon itself as shown at d^2 to avoid the presence of any edges having fins thereon which might scratch the fingers of the user. Furthermore the hold d' will limit the movement of the plate d toward the guard portion of the plate a by engaging with the back edge of said plate, which latter is folded upon itself as shown at a^3 to reinforce the back edge of the plate and at the same time avoid the presence of any sharp edges at this point. Secured to the under side of the plate a by being soldered or otherwise permanently united thereto, is a tubular handle f also made of sheet metal.

The guard plate may be formed by means of dies, the projections $e-e'$ being readily pressed up from the body of the plate a in any desired form to secure the necessary engagement therewith with the back edge of the blade.

In mounting the blade b , it is inserted beneath the keepers c adjacent the guard a' , the blade being raised slightly to permit it to pass over the gage tongues a^2 , the ends of said keepers being mitered as shown, to afford clearance for this purpose and to facilitate the insertion of the retaining plate d beneath same at the opposite edge of the plate. When the blade is thus positioned upon the plate a , the retaining plate d is inserted beneath the keepers c and forced downwardly slightly to bring the forward edge thereof above the projections $e-e'$. Said plate d is then forced toward the guard a' until the hand-hold d' thereon engages the rear edge of the plate a . The tongues a^2 will prevent any displacement of the blade during this movement of the retaining plate.

By accurately positioning the projections $e-e'$ and the tongues a^2 , the mere mounting of the plate d upon the plate a by means of the keepers c will accurately position the cutting edge of the blade in relation to the guard a' . Hence considerable accuracy is required in the formation of the projections $e-e'$ and the lugs a^3 to insure the desired parallelism in the guard a' and the cutting edge of the blade b , particularly as no means for adjustment of the blade is afforded.

The tongues a^2 might be dispensed with, and the thumb of the user relied upon to

secure the desired accurate positioning of the blade with relation to the guard, but particularly with a cheap razor, it is advisable to provide every safeguard to insure accuracy in the positioning of the blade and prevent the fingers of the user being cut in mounting the blade upon the guard plate.

When the blade is dulled it may be readily replaced by removing the retaining plate d and mounting a new blade upon the plate a in the manner above referred to.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:

1. A safety razor comprising a sheet metal guard plate having one longitudinal edge thereof turned upon itself to form a guard for the edge of the razor blade, and having the opposite side edges thereof turned in the opposite direction to form guide keepers extending at right angles to said guard at opposite edges of said guard plate, said guard plate having rectilinearly arranged, upwardly extending projections between said guide keepers, and a retaining plate slidably mounted in said guide keepers and adapted to engage said projections, whereby said retaining plate adjacent the cutting edge of the blade, will be forced into engagement therewith to bind said blade upon said plate.

2. A safety razor comprising a sheet metal guard plate having one longitudinal edge thereof turned upon itself to form a guard for the edge of the razor blade, and having the opposite side edges thereof turned in the opposite direction to form guide keepers extending at right angles to said guard at opposite edges of said guard plate, said guard plate having rectilinearly arranged, upwardly extending projections between said guide keepers and upwardly turned front gages adjacent the opposite edges of said guard and adapted to restrain movement of said blade forwardly of said guard and insure its accurate alignment therewith, and a retaining plate slidably mounted in said guide keepers and adapted to engage said projections, whereby said retaining plate adjacent the cutting edge of the blade, will be forced into engagement therewith to bind said blade upon said plate.

3. A safety razor comprising a sheet metal guard plate having one longitudinal edge thereof turned upon itself to form a guard for the edge of the razor blade, and having the opposite side edges thereof turned in the opposite direction to form guide keepers extending at right angles to said guard

- at opposite edges of said guard plate, said guard plate having rectilinearly arranged, upwardly extending projections between said guide keepers, and a retaining plate 5 slidably mounted in said guide keepers and adapted to engage said projections, whereby said retaining plate adjacent the cutting edge of the blade, will be forced into engagement therewith to bind said blade upon 10 said plate, said retaining plate having a downwardly turned edge forming a hand-hold along one edge thereof adapted to engage said guard plate and limit the movement of said retaining plate toward the cutting edge of the blade. 15
4. A safety razor comprising a sheet metal guard plate having one longitudinal edge thereof turned upon itself to form a guard for the edge of the razor blade, and having 20 the opposite side edges thereof turned in the opposite direction to form guide keepers extending at right angles to said guard at opposite edges of said guard plate, said guard plate having rectilinearly arranged, 25 upwardly extending projections between said guide keepers and upwardly turned front gages adjacent the opposite edges of said guard and adapted to restrain movement of said blade forwardly of said guard 30 and insure its accurate alinement therewith, and a retaining plate slidably mounted in said guide keepers and adapted to engage said projections, whereby said retaining plate adjacent the cutting edge of the blade, 35 will be forced into engagement therewith to bind said blade upon said plate, said retaining plate having a downwardly turned edge forming a hand-hold along one edge thereof adapted to engage said guard plate and limit the movement of said retaining plate toward the cutting edge of the blade. 40
5. A safety razor comprising a sheet metal guard plate having the opposite longitudinal edges thereof turned downwardly and 45 upon said plate to reinforce the plate adjacent said edges and form a guard for the edge of the razor blade adjacent one of said edges, and having the opposite side edges thereof turned upwardly and inwardly to 50 form guide keepers extending at right angles to said guard, said guard plate having rectilinearly arranged, upwardly extending projections between said longitudinal edges and said guide keepers, a retaining plate 55 slidably mounted in said guide keepers and adapted to pass over and engage said projections and be forced into engagement with the cutting blade to bind it upon said guard plate, one edge of said plate being turned 60 to form a hand-hold adapted to engage the edge of said guard plate and limit the movement of said retaining plate toward said cutting edge, and a sheet metal handle 65 permanently secured to the under side of said guard plate.

In witness whereof I have hereunto affixed my signature, in the presence of two subscribing witnesses, this 29th day of January, 1920.

HENRY SCHLESINGER.
